UNITED STATES PATENT OFFICE

137,404

DESIGN FOR A DIAL FOR A TIMEPIECE

Leo Y. Booharin, San Francisco, Calif.

Application July 30, 1943, Serial No. 110,804

Term of patent 14 years

To all whom it may concern:

Be it known that I, Leo Y. Booharin, a citizen of the United States, residing in the city and county of San Francisco, and State of California, have invented a new, original and ornamental Design for a Dial for a Timepiece, of which the following is a specification, reference being had to the accompanying drawing, forming part thereof.

Fig. 1 is a plan view of a dial for a timepiece showing my new design.

Fig. 2 is an edge view of the dial shown in Fig. 1.

The shading indicated on the dial as seen in Fig. 1 is intended to represent a shade or tone different from that of the unshaded portions.

I claim:

The ornamental design for a dial for a timepiece, as shown and described.

LEO Y. BOOHARIN.
